DETACHABLE SHOE HEEL LIFT

Edmund R. Nebeling, Woodhaven, N. Y.

Application March 29, 1934, Serial No. 717,961

1 Claim. (Cl. 36—42)

This invention relates to shoe heels, and more particularly it pertains to a new and novel means whereby a shoe heel lift may be detachably associated with a shoe heel.

5 It is one object of the invention to provide a new and novel means whereby a lift may be readily removed from a shoe heel, thereby providing for interchangeability of the lift of a shoe heel.

10 A further object of the invention resides in a novel construction whereby the fastening or securing means of the lift is relieved of all excessive pressure or strain under operating conditions.

15 Still a further object of the invention resides in a new and novel method of securing an attaching means to the lift of a shoe heel.

With the above and other objects in view, the nature of which will be apparent as the description progresses, reference will be had to the accompanying drawing wherein:

20 Figure 1 is a fragmentary view in elevation of a shoe, showing a heel having a removable lift constructed in accordance with the present invention.

Figure 2 is a fragmentary view in elevation, taken from the left hand side of Figure 1,

Figure 3 is a plan view of the tread end of the heel, the lift being removed,

25 Figure 4 is a plan view of the heel abutting face of the lift,

Figure 5 is an enlarged vertical sectional view taken substantially on the line 5—5 of Figure 2,

30 Figure 6 is a similar view taken substantially on the line 6—6 of Figure 1,

Figure 7 is a horizontal sectional view on an enlarged scale taken substantially on the line 7—7 of Figure 2,

35 Figure 8 is an enlarged transverse sectional view of that member of the fastening means which is carried by the heel lift,

Figure 9 is an enlarged plan view of that member of the fastening means which is carried by the lift, and

40 Figure 10 is a distended perspective view of one member of the fastening means.

Referring to the drawing by reference character, the numeral 12 designates the rear or counter portion of a shoe, the reference character 14 designating a shoe heel, the lift thereof being designated 16.

45 The lift 16 is of a type which is readily removable from the heel and this feature of the invention permits of ready interchangeability of the lifts from one heel to another or the complete dis-

carding of a heel lift and its replacement by another lift.

In order to provide for ready detachment of the heel lift from the heel, I have provided a lift securing means in the form of two interengaging members, one of which is carried by the heel and the other being carried by the lift. This attaching means is almost identical in construction with a separable fastener illustrated in Patent No. 1,357,795 granted to me November 2, 1920, and I will not, therefore, describe the same other than in a cursory manner and to such extent as is necessary to its adaptation to the present purpose.

The attaching means consists of two interengaging members A and B. The member A comprises a housing 18, which is formed with a flange 20 having a cut-out portion 22. A filling plate 24 is placed in the bottom of the housing 18, and on top of this filling plate 24 is placed a 20 guide plate 26, cut out as at 28, to provide guiding means for a latch member 30. The latch member 30 has a reduced extension 32, which terminates in an angular end 34, providing an operating member by which the latch may be 25 moved in the guide plate 26. The guide plate 26 is cut out as at 36 to receive the reduced extension 32 of the latch member 30. A cover plate 38 holds the several described parts in their operative position, and the cover plate may be 30 retained in position by turning over the edge of the flange of the housing as at 40. Each of the several elements just described, except the latch member 30, is provided with a plurality of openings 42, which when the several parts are assembled, register with one another for the reception of fastening means, herein illustrated as nails or tacks 44. The housing 18, filling plate 24, and the cover plate 38, are each provided with spaced openings 46, preferably circular in form and the 40 side edges of the cut out portion 28 of the guide plate 26, as well as the side edges of the latch member 30, are provided respectively with notches 48 and 50, which are preferably semi-circular in form. The several parts are so assembled that 45 the several openings 46, and the notches 48, of the guide plate are in registration with each other to provide openings C, when the latch member 30 is extended, as illustrated in Figure 3, it being understood that at this time, the notches 50, of 50 the latch member 30, will coincide with the notches 48, of the guide plate 26.

The other member B, of the fastening means consists of a plate 52, of rigid or relatively stiff metal and it carries two posts 54, which are 55

adapted for reception in the openings C, of the member A. These two posts are cut out as at 56, see Figure 6.

The member A, of the fastening means is mounted in the tread end of the heel 14, within a recess 58 therein, which recess is of a depth which is greater than the thickness of the member A. This construction provides a seat or the like 60, upon the tread end of the heel, which seat lies in a plane beyond the outer face of the member A of the fastening means, as illustrated by the space 62, in Figure 5.

The member B, of the fastening means is carried by the lift member 16, and to secure the same to the lift member, I provide on the outer edge of the plate-like member 52, a plurality of very closely adjacent prongs 64. Each of these prongs is provided on its outer end with a piercing point 66, and where the prongs join the main body portion of the plate, each is provided with oppositely curved portions which provide oppositely disposed locking shoulders 68, upon the side edges of each prong. In attaching the plate 52, to the lift 16, the prongs 64 are bent at an angle to the body portion of the plate, as illustrated in Figure 6, in such a manner that when pressure is applied to the plate 52, the prongs 64, and their locking shoulders 68, will be embedded in the material of the lift 16, which is preferably leather. The locking shoulders 68 serve to anchor the prongs in the material of the lift, and by providing a large number of prongs, closely associated with one another, the plate is not only firmly secured to the lift 16, but the plate is held in close contact throughout its defining edge with the face of the lift 16. Still another advantage resulting from this construction resides in the fact that by using the prongs in large numbers together with the locking shoulders, I am enabled to make the prongs comparatively short or at least short enough that they do not pass entirely through the heel lift 16.

In placing the lift upon the heel, the latch member 30 is moved to its extended position as illustrated in Figure 3. The posts 54 of the member B are then positioned in the openings 46, after which the latch member is moved to its innermost position whereupon the side edges 50 of the latch member pass into the cut out portions 56, of the posts 54, and thereby prevent withdrawal of the posts 54, from the openings 46, and thus locking the interengaging members A and B together. The latch member 30 has a projecting lug or member 70, which engages in an opening 72 in the filler plate 24, when the latch plate is in its innermost position, and this means serves to retain the latch plate in its holding position.

Also, means is provided to prevent relative sliding or rotary movement of the lift and heel, and this means preferably consists of a portion 76, of the turned over portion 40, of the flange

22, which portion is left standing up and is in such a position that it passes through the cut out portion 78, of the plate 52, and into biting engagement with the lift 16, thus preventing relative movement between the lift and the heel. 5

When it is desired to remove the lift from the heel, it is only necessary to insert a tool or similar article behind the member 34, of the latch plate 30, and exert a slight outward pressure thereon. This will move the latch plate to its extended position, whereupon the notches 50, will coincide with the notches 48, and the posts will be free to pass from the openings C. 10

The plate 52, is of a greater transverse dimension than is the recess in the heel in which the member A, is positioned, and thus when the lift is in position upon the heel, the plate 52, engages and bears upon the seat 60, which defines said recess, and since, as before stated, this plate is of stiff or rigid material, the pressure occasioned by the weight of the person wearing the shoe, is transmitted directly to the heel by the plate 52, and the fastening means is relieved of all strain incidental to the wearing of the device. 15

From the foregoing, it will be apparent that the present invention provides a new and novel heel lift attaching and fastening means which permits of the ready removal and replacement of a shoe heel lift, which is simple in operation and which can be constructed in a strong and durable manner. 20

The invention has been herein illustrated in its preferred embodiment, in which it has been applied to the lift of the heel of a lady's shoe. It is to be understood, however, that it may also be incorporated in lifts of larger sizes, such as are employed in connection with men's shoes or it may also be employed as a means for attaching a heel to a shoe instead of attaching a lift to a heel. 25

Having thus described the invention, what is claimed is:

A detachable lift for shoe heels comprising in combination, a shoe heel, a lift therefor, and a two-part fastening means for said lift, one part 45 of said fastening means being carried by the shoe heel and including a housing, a tongue projecting from said housing, the other part of said two-part fastening means being carried by the lift and including a rigid plate having a portion 50 thereof removed to permit of the afore-mentioned projecting tongue of the housing of the other part of the fastening means to engage the lift to prevent turning or sliding movement thereof relative to the shoe heel, studs on the plate penetrating 55 the housing, a locking plate slidably mounted in the housing and having edgewise locking engagement with the studs and cooperating means carried by the plate and an element within the housing for securing the plate against accidental 60 sliding movement.

EDMUND R. NEBELING.
